Application August 19, 1935, Serial No. 36,820

25 Claims. (Cl. 235—144)

My invention relates to locked pick counters. It has among its objects to provide an improved pick counter of the reset type adapted to be locked during operation and unlocked to permit resetting, and such a counter having improved mechanism associated with it to prevent tampering with the resetting mechanism to fraudulently advance the count both while the counter is locked and while it is unlocked. A further object of my invention is to provide improved locking and resetting mechanism for pick counters having improved means associated therewith for preventing advance of the count by a blow on the resetting mechanism, either following resetting and before locking or following locking of the mechanism. A still further object includes the provision of improved and simplified locking means preventing removal of the key following initiation of a resetting movement until the counter wheels have been completely reset to their initial zero position, and also preventing such removal of the key until the resetting mechanism has been operated to disconnect the operative connection between the driving elements of the resetting mechanism and the counter wheels. A still further object is to provide improved and simplified reset locking mechanism for a multiple pick counter having a common locking means and eliminating the need for a transverse locking member extending across the axes of the resetting shafts of the several counters, required in previous constructions. These and other objects and advantages of my improved construction will, however, hereinafter more fully appear.

In the accompanying drawings I have shown for purposes of illustration two embodiments which my invention may assume in practice.

In these drawings:

Figure 1 is a plan view of one form of my invention as applied to a double pick counter;

Fig. 2 is a similar view with a portion of the cover broken away showing the locking mechanism;

Fig. 3 is a view of the locking mechanism of Fig. 2 in the unlocked position;

Fig. 21 is a sectional view similar to Fig. 17 but showing the cooperating locking members 20 in the zero position of the parts following resetting and before locking;

Fig. 22 is a detail of a modified form of no-reverse mechanism, and

Figs. 23 and 24 are sectional views taken on 25 line 23—24 of Fig. 22.

In the construction illustrated in Figures 1—14a, I have shown my invention applied to a double 30 pick counter mechanism of a well known type including a casing comprising a body 1 and a removable cover 2 and having two like counters generally indicated at 3 and 4 therein. These counters are mounted on parallel shafts 6 and 7 journaled in the ends of the casing and are adapted to be driven selectively from a counter

drive shaft 8 by a usual clutch mechanism, not shown, depending upon the position of connection of a usual manually adjustable control member 9; one counter, herein the counter 3, being connected for use on the day shift and the other 40 for use on the night shift. Each of said shafts has a resetting member 10 located externally of the casing by which either counter may be reset to zero, as will be hereinafter explained. The counters 3 and 4 are adapted to be locked during

counting operation by improved locking mechanism, hereinafter more fully described, including a lock 11 and key 12, as herein shown of the usual "Yale" or pin tumbler type, controlling the operation of the resetting members 10. 45

Referring to the counters 3 and 4, it will be noted that each of these includes a plurality of coaxial counter wheels operatively connected by the usual tens-transfer mechanism and that the two counters are identical in construction. Using 50

the counter 3 for purposes of description, it will be noted that the same comprises three counter elements 13, 14 and 15, each including a number wheel operatively connected through usual tens- 5 transfer mechanism of the locking type so as to register the rotation of the driving shaft 8 in terms of multiples of picks woven, with each unit on the wheel 15 representing a predetermined number of picks, as, for example, one thousand 10 picks, each unit on the wheel 14 representing ten thousand picks, and each unit on the wheel 13 representing one hundred thousand picks.

Considering more particularly the construction 15 of one of the counter elements 13, 14 and 15, it will be understood that each of these is identical in construction so that reference to only one is necessary. Considering counter element 13 of counter 3 it will be noted that this element, as shown in Figures 6, 7 and 8, includes a sleeve 16 20 on which the number wheel 17 is fixed and which also has fixed thereto a locking disc 18 and a mutilated transfer gear 19 on the opposite side of the locking disc 18 from the number wheel. Also, as is usual in such units, a reset pawl 20 in 25 the disc 18 is normally pressed by a spring 21 through an aperture 22 in the sleeve 16 ready to engage with a longitudinal groove 23 in its supporting and resetting shaft 6, as will be readily understood from an inspection of Figure 6 in 30 which the groove is slightly displaced from the pawl 20. Further, it will be noted that a driving gear 24 is rotatably mounted on the opposite end of the sleeve 16 from the mutilated transfer gear 19 and through a pair of spring pressed pawls 25 35 is adapted to cooperate in a usual way with a cup-shaped ratchet member 26 which is disposed within a recess in the face of the number wheel 17 adjacent the gear 24. Thus, it will be evident that with the several counter units 13, 14 and 15 40 of counter 3 operatively connected by usual transfer pinions 27, the counter will count progressively in the usual manner, and the number wheels thereof will be reset to zero position, shown in Figure 1, upon a complete rotation of the shaft 6 45 by its resetting member 10 in the resetting direction indicated by the arrow in Figure 2, during which the pawls 20 of the several counter elements will be picked up by the groove 23 all in a well known manner.

In a copending application, now issued as 50 Patent No. 2,040,031, and assigned to the assignee of this application, a pick counter of this general type is shown and described in detail in which fraudulent advance of the count is prevented, both when the counter is locked and when it is 55 unlocked, and reference is made to this prior application. The construction shown herein prevents fraudulent advance of the count by a dishonest operator even when such an operator 60 possesses a key to the counter mechanism, and provides in a simpler and less expensive locking and resetting mechanism, the advantageous features of said earlier filed application. For instance, in the present construction the longitudinally reciprocable bar extending transversely 65 of the resetting shafts, required in the prior construction, is entirely eliminated.

In this preferred form of my invention, the lock 70 11 is common to both counters 3 and 4 and is supported on a bracket 28 (Figure 13) fixed to the inner wall of the casing between the resetting shafts 6 and 7 adjacent the ends thereof carrying the resetting members 10, and includes a stationary barrel 29 formed integral with the bracket 75 28 and a lock plug 30 rotatable therein having a

key slot 32. As is usual in this type of lock, the lock plug 30 can not be rotated in the barrel until the key 12 has been inserted in key slot 32; and, after the lock plug has been turned by the key even slightly, the key can not be withdrawn until the lock plug has been returned to its normal locking position. Herein a locking plate 34 is secured to the bottom end of the lock plug 30 for movement therewith when the latter is turned by the key 12 and is held against rotation relative thereto 10 by means of a pin 35 (Figure 13).

Rotatable locking members 37 (Figure 10) are fixed on the resetting shafts 6 and 7 in position to cooperate with the key controlled locking plate 34. For this purpose, supporting sleeves 38 15 (Figures 11 and 12) are fixed to said shafts between the counter elements 13 and the end wall of the casing by pins 38a which extend through flanges 39 of said sleeves and the respective shafts 6 and 7. Sleeves 38 have flattened peripheral portions 40 which cooperate with corresponding flattened portions 41 in the apertures 42 of said rotatable locking members to position the latter against rotation on said sleeves, the rotatable locking members being suitably supported against longitudinal movement on the sleeves by means of tubular spacers 43 and 44 which extend between the enlargement 39 at one end of said sleeve and a ratchet wheel 45 adjacent the casing wall. It will be noted that the ratchet wheels 45 are likewise fixed to the sleeves 38, having apertures 46 30 provided with flattened portions 47, as in the case of the locking members 37. The rotatable locking members 37 are also provided with rectangular notches 48 in their external peripheries which, 35 in the zero position of the resetting shafts following resetting of the counter elements to zero and prior to locking, are disposed in the horizontal plane including the axes of resetting shafts 6 and 7 and confront each other.

Considering more in detail the cooperating locking plate 34, briefly referred to above, it will be noted that this plate moves in the horizontal plane including resetting shafts 6 and 7 and has diametrically opposite extensions 49a and 49b, the 40 diagonally disposed edge portions 50a and 50b of which are oppositely reflexed upwardly and downwardly, respectively, out of the plane of the plate 34. It will also be noted that when the locking plate 34 is moved clockwise by the key 12 50 from the unlocked position of the mechanism shown in Figure 3, into locking relation with the rotatable locking members 37, the leading edges 51a and 51b of the plate, will be aligned with and will enter the notches 48 of members 37. As the locking plate 34 is moved to the mechanism locked position shown in Figure 4, due to the vertical deflection of the trailing edge portions 50a and 50b, the plate 34 has a camming action on the rotatable locking members 37 rotating both of the latter in a clockwise direction as viewed from the left in Figure 2, i. e., in a direction opposite to the direction of rotation of the shaft during resetting as indicated by the arrows in Figure 2. The rotation of the resetting shafts 6 and 7 due to the camming action of plate 34, as herein shown, is sufficient to rotate the resetting shafts 6 and 7 reversely through an angle of approximately 12 degrees into a position in which the resetting grooves 23 are withdrawn from the resetting pawls 20 as illustrated in Figures 4 and 6.

Mechanism is also provided, including the ratchet wheel 45 previously mentioned, for preventing reverse rotation of the resetting shafts 6 and 7 in certain positions of the latter. As shown 75

most clearly in Figure 4, the ratchet wheels 45 are provided with a series of teeth 53, herein four in number, which cooperate with spring pressed pawls 54 carried by the end wall of the casing 1, the pawls riding over the teeth and the untoothed portion on the periphery of the ratchet wheels 45 and dropping in back of each tooth as said wheels are rotated past the stationary pawls during resetting. Thus, it will be evident from an inspection of Figure 4 that if a resetting shaft is rotated in a resetting direction enough to advance a number wheel 17 even slightly, the pawl 39 associated with that counter will drop in back of a tooth in such manner as to prevent a return movement of the shaft and compel the operator to continue the resetting movement before he can lock the counter mechanism. Here, it will be noted that the position of the pawls following a complete resetting movement of the number wheels to zero is such as to permit the limited reverse rotation of the ratchet wheels due to the camming action above described.

In the use of this form of my invention, it will be understood that the counter mechanism is locked during operation of the loom and that the supervisor at the end of the day or the week, after recording the readings of the day or night counter, or, if desired, of both counters, is able to unlock the counter mechanism by inserting the key 12 in lock 11 and turning the key to rotate the locking plate 34 from the mechanism locked position of Figure 2 into the unlocked position of Figure 3, releasing both rotatable locking members 37. He is then able to rotate either or both shafts 6 and 7, as may be desired, in the resetting direction indicated by arrows in Figure 2 and reset one or both of the counters to zero position by resetting members 10. Following a completed resetting movement of either or both counters, and only then, can the key be turned again to the mechanism locked position of Figure 2 in which it can be withdrawn. Thus the weaver is not only prevented from tampering with the resetting mechanism, but carelessness on the part of the supervisor is also prevented, since he can not lock the mechanism and withdraw his key until the counter or counters he has reset have been properly returned to zero position.

In Figures 15-24, I have illustrated another construction which may be used advantageously when it is not desired to reset the counters 3 and 4 separately. In this modified construction only one resetting member 10 is provided, the resetting member on shaft 6 being omitted and this shaft being shortened to terminate in the casing wall.

Both counters 3 and 4 are reset by the single operating member 10 provided on shaft 7. To this end each resetting shaft has a spur gear 56 carried on its sleeve 38 in place of the ratchet wheels 45, each of said gears, as shown most clearly in Figure 17, having an aperture provided with a flattened portion 58 which corresponds with the flattened portions 40 of the sleeves. An intermediate idle gear 59 on drive shaft 60 operatively connects the gears 56 and has a spring pressed pawl 61 which is carried by the casing cooperating with the teeth thereof to prevent reverse rotation of the gear train. It will be evident that, when the wing nut 10 is turned to rotate shaft 7 in the resetting direction, shaft 6 will be rotated in the same direction to reset both counters in unison.

Due to the operative connection of the two counter shafts through the train including gears 56 and 59, the locking means, in this construction,

cooperates directly with the resetting mechanism of one counter only, herein the counter 4. Accordingly, a lock 62 having a key 63 is provided in the corner of the casing adjacent the resetting shaft 7. This lock is of the usual "Yale" or pin tumbler type, previously described, and has a locking plate 64 (Figure 19) which is fixed to the lock plug 30 above the barrel 29 in the space between the top of said barrel and the cover 2 (Figure 21). The plate 64 is provided with a projection 65 which lies in the slot 32 in the lock plug so that upon insertion of the key 63 in said slot and rotation of the lock plug by the key, the locking plate 64 will be swung from the locking position shown in Figure 16, in the direction of the arrow indicated in that figure, into unlocked position. A cooperating rotatable locking member 66 is provided on the sleeve 38 of shaft 7, secured against rotation relative thereto by a flattened portion 67 cooperating with the flattened portion 40 of said sleeve. The locking member also has a flattened portion 68 on its external periphery, which, in the normal locked position of the mechanism, is horizontally disposed at the top, as shown in Figure 17, beneath the locking plate 64. It will be evident that in this position of the locking plate 64 in which it overlies the flattened portion 68, the counter resetting shaft 7 of counter 4, and hence also the resetting shaft 6 of counter 3, are locked against rotation.

As in the preferred form above described, if the counter is locked with the resetting mechanism in the zero position of the number wheels immediately following resetting, i. e., with the reset pawls 20 in the resetting grooves 23, it is possible to advance the count by tapping the resetting wing nut 10 to jump ahead one or more of the counter wheels 17 while the resetting mechanism is locked. This form of cheating is prevented in this modified construction, as in the above construction, by means for reversely rotating the resetting shafts during locking of the mechanism. It will be noted (Figure 21) that in the position of the locking disc 66 immediately following a resetting operation and prior to locking, the flattened portion 68 of the rotatable locking disc is rotated beyond its normal locking position shown in Figure 17 and is angularly related to the horizontal locking plate 64. Accordingly when the locking plate 64 is swung from the unlocked position of Figure 21 to the locking position of Figure 16, the rotatable locking member 66 will be rotated reversely into a position in which the resetting grooves 23 of shafts 6 and 7 are withdrawn from engagement with the resetting pawls 20, as shown in Figure 6. In this position of the parts a blow against the resetting wing nut 10 can not be transmitted through the grooves 23 to the resetting pawls, and fraudulent advance of the counter wheels by this method is prevented. The lower corner of locking plate 64 is preferably bevelled, as indicated at 69, where it engages the rotatable locking member 66, as illustrated most clearly in Figures 19 and 20. This movement of the locking plate is limited by the margins 70 in the locking plate 64 which engage a pin 71 in the bracket of the lock.

In operation this modified construction does not differ, except as above pointed out, from the preferred construction previously described, except that in the modified construction the counters must be reset in unison and can not be separately reset as in the preferred construction.

In Figures 22 to 24 inclusive I have illustrated a modified form of no-reverse mechanism of the

ball clutch type which, while not preferred, may be used in place of the pawls and ratchets illustrated in the two embodiments of my invention. As shown herein, the ball clutch mechanism is 5 illustrated in connection with the locking structure of Figures 1 to 14a. It will be noted that the sleeve 38 of that locking mechanism is replaced by a special sleeve 72 which is secured to the resetting shaft, as the shaft 6, by a pin 73. 10 The sleeve is formed with a reduced end portion adjacent the counter element 18 forming a shoulder 74 against which the locking member 37 abuts, and is also provided with a flat portion 40 which cooperates with the corresponding flat portion 41 15 of the locking member, as previously described. A spacing member 75 is held in place by the pin 73 and serves to hold the locking member in place against the shoulder 74. The sleeve 72 has tapered, circumferential ball receiving grooves 76, 20 herein three in number, at its opposite end, adjacent the casing end wall, in each of which a spring pressed ball 77 is disposed in position to frictionally engage a cup-shaped ball retaining member 78 carried by the casing wall, which permits 25 free rotation of the sleeve relative thereto in one direction while gripping the same by the clamping action of the balls upon opposite rotation of the sleeve in a manner well known in friction clutches of this type. The cup-shaped ball retaining member 78 has its end wall partly removed, forming an 30 aperture 79 therein having opposed flat surface edges 80 which receive somewhat loosely therebetween the corresponding opposed, flat surfaces of a hub 81 formed on the casing wall and extending 35 into said aperture 79. It will be evident from Figure 23 that, as a consequence of the loose fit of the corresponding flat surfaces on 81 and 78, the retaining cup 78 will permit the limited rotation of the resetting shaft 6 required by the locking mechanism, as previously described, to provide the important blow-proof feature of the present construction, while limiting this reverse rotation to that required for this purpose.

It will be understood that in both the above described embodiments of my invention, the counter mechanism is normally locked during weaving and that at the end of the day or the week, the supervisor is supposed to record the readings of one or both of the counters and to unlock and to 45 reset the same. He can not, however, lock the counter mechanism and withdraw his key once he has initiated resetting of either counter until that counter has been completely reset to zero. Thus, it will be evident that, while the weaver is prevented from fraudulent manipulation of the resetting mechanism, carelessness on the part of the supervisor is also prevented by requiring a 50 complete resetting of either counter and locking of both counters before he can withdraw his key. 55 Further, with the above described mechanism an operator obtaining a key can not advance a legitimate count by manipulating the resetting mechanism due to the presence of the ratchet and pawl construction which, upon even a slight movement of the resetting mechanism in a resetting direction, results in one of the spring pressed pawls dropping behind a tooth, thus, requiring a 60 complete resetting movement to zero. Thus an operator attempting to cheat in this manner in order to avoid detection with the key in his counter will be obliged to wipe out even the count which he has legitimately woven and, after being thus penalized, will ordinarily not again attempt to cheat in this manner.

75 The presence of the ratchet and pawls also

prevents numerous other forms of cheating. For example, it prevents an operator who has obtained a key from fraudulently advancing the count at the beginning of the shift when the counter wheels are at zero position which, without the ratchet and pawls construction, he could do as follows: First, he would turn the counter resetting mechanism to read 999 and weave 2,000 picks with the key in the lock. The counter would then read 001. He would then turn the resetting member backward until he had picked up the lowest order number wheel, but without turning back enough to pick up the other number wheels. He would then turn ahead the resetting mechanism to the normal reset position thereof following which movement the number wheels would read 010. Then he would lock the counter mechanism and remove the key and really start his day's work with a credit for 10,000 picks. In the constructions above described, however, the operator would be unable to perform this type of manipulation since he can not turn back the wing nut 10. Instead with the construction shown in Figures 1-14a, he would be obliged to start by turning up 777 which would, of course, 20 subject him to a wholly unreasonable risk as a supervisor might come at any time while he was weaving the required 223,000 picks and to avoid detection, he would have to wipe out his whole count and start over. Obviously, if desired, instead of using four teeth, the number of teeth may be increased. In the modified construction including the gear 59 and pawl 61, reverse rotation of the resetting mechanism is prevented throughout the entire range of resetting movement.

Attention is also directed to the fact that in both constructions herein disclosed the mechanism is proof against fraudulent advance of the count by tapping on the resetting mechanism, 40 i. e., by striking the resetting member 10 a sharp blow by any suitable instrument, both when the counter is locked and when it is unlocked. Such advance when the counter mechanism is locked is prevented in my improved construction by 45 the camming action of the locking plate acting on the cooperating rotatable locking members to reversely rotate the latter and cause the resetting grooves 23 to be withdrawn from the reset pawls 20 before the counter mechanism can be 50 locked and the key withdrawn. Thus, it will be evident that it is impossible to transmit a blow on a resetting member 10 through the resetting shafts 6 and 7 to the ends of the reset pawls 20 in such manner that the counter wheels will be 55 advanced beyond zero.

Advance by tapping on the resetting member 10 immediately following resetting and prior to locking is prevented by the no-reverse mechanism including the spring pressed pawls acting 60 on the ratchet wheels 45 or the gear 59. These cooperating members provide sufficient frictional restraint on the resetting mechanism to make it impossible for an operator to advance the counter wheels by a blow by holding the unlocked resetting member 10 and striking a blow since, due to this frictional restraint, such a severe blow must be struck that the resetting shaft will be advanced sufficiently to allow one of the pawls to drop behind the next adjacent tooth, thus requiring a complete resetting movement of the resetting mechanism in order to permit locking and withdrawal of the key.

It will further be evident that as a result of the present improvements I have provided a sim-

plified locked counter mechanism of the pick counter type including a plurality of counters having a common lock cooperating therewith in an improved manner and without the necessity 5 for the reciprocable locking member. Further by reason of the pawls and ratchets and the blow-proof structure, above described, a wholly new cooperation is provided between the resetting mechanism and the locking mechanism 10 which produces an improved locked pick counter and one which an operator can not fraudulently advance even if he has a key. These and other objects and advantages of my improved construction will, however, be clearly apparent to those 15 skilled in the art.

While I have in this application specifically described two embodiments which my invention may assume in practice, it will be understood that the same are shown for purposes of illustration and that the invention may be modified and embodied in various other forms without departing from its spirit or the scope of the appended 20 claims.

What I claim as new and desire to secure by 25 Letters Patent is:

1. In a locked pick counter mechanism, two 30 counters each having operatively connected counter elements, rotatable resetting mechanism for said counter elements including resetting shafts rotatable to reset said counter elements to zero 35 and operating members for separately rotating said shafts, and means for locking said resetting mechanism against resetting movement including locking portions rotatable with said shafts, a lock and key located between said resetting shafts and controlling the resetting of said counter elements, and a swinging locking member controlled by said key and cooperating directly with said rotatable locking portions.

2. In a counter having operatively connected 40 counter elements, resetting mechanism for said counter elements including an operating member for the latter having an axial support, a locking portion carried by said resetting mechanism, locking means controlling the resetting of said 45 counter elements comprising a single lock and key, and swinging locking means controlled by said key and movable about an axis located in a plane perpendicular to the axis of said operating 50 member into engagement with said locking portion to lock said resetting mechanism.

3. In a counter having operatively connected 55 counter elements, rotatable resetting mechanism for said counter elements including a resetting shaft and an operating member for rotating the latter, a locking member rotatable with said resetting mechanism, a lock having a key, and swinging cam means operable following resetting and rotatable by said key about an axis perpendicular to the axis of said resetting mechanism for engaging and rotating said locking member and said resetting shaft reversely during locking of said mechanism by said key.

4. In a counter having operatively connected 60 counter elements, resetting mechanism for said counter elements including a rotatable resetting shaft and an operating member for rotating the latter, a locking member rotatable with said shaft, a single lock having a key controlling the locking and unlocking of said resetting mechanism, and swinging locking cam means positively 65 oppositely actuated by said key during locking and unlocking movements of the latter for engaging said locking member in the position of the latter following a resetting movement by said

operating member and cooperating therewith to reversely rotate said resetting shaft as said resetting mechanism is locked.

5. In a counter having operatively connected 5 number wheels, resetting mechanism for said number wheels including a resetting shaft rotatable to reset said wheels to zero and an operating member for rotating said shaft, and means for locking said resetting mechanism against resetting movement including a locking 10 member rotatable with said shaft and a single lock and key, said lock having a locking cam member cooperating directly with said rotatable locking member in the zero reset position only of said number wheels to rotate said rotatable 15 locking member and said resetting shaft reversely in response to the locking movement of said key.

6. In a counter having operatively connected 20 number wheels, resetting mechanism for said wheels including a resetting shaft having an operative connection with said wheels and rotatable in one direction to reset said wheels to zero position and an operating member for rotating said shaft, and means for unlocking said resetting 25 mechanism for resetting movement and following a resetting movement for disconnecting the operative connection between said number wheels and said resetting shaft and locking said mechanism against resetting movement including a locking member rotatable with said resetting shaft, a single lock having a key, and a cam plate carried by said lock arranged to engage said rotatable locking member and rotate the latter in the direction opposite to resetting movement into locking position by the locking 30 movement of said key.

7. In a locked pick counter mechanism, a plurality of counters each having operatively connected counter elements, separate resetting mechanism for the counter elements of each 40 counter including an operating member for each of the latter, a locking member carried by the resetting mechanism of each counter having a locking aperture, a lock having a key, and swinging means operated by said key and cooperating 45 with said locking apertures to unlock said resetting mechanisms and to lock the same following resetting.

8. In a counter having operatively connected 50 counter elements, rotatable resetting mechanism for said counter elements including an operating member for rotating the latter, a locking member rotatable with said resetting mechanism having a locking aperture, a lock having a key, and means operated by said key and movable thereby 55 into and out of said locking aperture to lock and unlock said resetting mechanism including a swinging cam cooperating with said locking aperture to reversely rotate said resetting mechanism following resetting and during locking. 60

9. In a counter having operatively connected 65 counter elements, resetting mechanism for said counter elements including a resetting shaft and an operating member for the latter, a locking member rotatable with said resetting mechanism having a peripheral locking portion, a lock having a key, and means operated by said key to lock and unlock said resetting mechanism including a cooperating locking member rotatable by said key into and out of engagement with 70 said portion and having a cam surface acting on said rotatable locking member to rotate the latter reversely during locking movement of said key following resetting.

10. In a locked pick counter mechanism, two

- counters including adjacent resetting shafts having rotatable locking portions, a key operated lock located between said shafts having a lock barrel rotatable on an upright axis in a plane perpendicular to said resetting shafts, and cooperating locking means for locking and unlocking said shafts in response to locking and unlocking movements of said key including a member rotatable with said lock barrel and movable in a plane perpendicular to the axis of said barrel and having operative engagement with said locking portions between said shafts.
11. In a locked pick counter mechanism, a casing open at the front and having a cover forming a closure for its open front, two counters within said casing including parallel resetting shafts journaled in said casing longitudinally thereof having rotatable locking members, reset operating members for said shafts located externally of said casing, a lock in said casing located between said resetting shafts including a lock barrel rotatable about an axis perpendicular to said shafts and a key insertable therein through said front cover and rotatable about said axis, and means controlled by said key including a swinging member rotatable with said lock barrel and having portions thereon cooperating with said locking members in the space between said shafts.
12. In a locked pick counter mechanism, two counters having adjacent resetting shafts, locking members rotatable with said shafts, a lock located between said shafts having a key, and a swinging locking member controlled by said key engaging with both of said rotatable locking members to lock and release said resetting shafts in response to locking and unlocking movements of said key.
13. In a locked pick counter mechanism, two counters having adjacent resetting shafts, locking members rotatable with said shafts, a lock located between said shafts having a key, and a swinging locking member controlled by said key engaging with both of said rotatable locking members to lock and release said resetting shafts in response to locking and unlocking movements of said key, said rotatable and swinging locking members having cooperating portions engageable to rotate said resetting shafts reversely during locking movement of said key.
14. In a locked pick counter, a plurality of counter mechanisms each including a plurality of operatively connected number wheels, independently operable resetting mechanisms for said counter mechanisms including axial rotating elements and cooperating pawl elements within said wheels, a lock having a key, a member carried by said lock and rotatable with said key and having a plurality of arms, and means for separating said elements to blowproof said wheels and for preventing operation of said resetting mechanisms having elements cooperating with said arms.
15. In a locked pick counter, a plurality of counter mechanisms each including a plurality of operatively connected number wheels, independently operable resetting mechanisms for said counting mechanisms including axial rotating elements and cooperating pawl elements within said wheels, a lock having a key, a member carried by said lock and rotatable with said key and having a plurality of arms, means for separating said elements to blowproof said wheels, and means for preventing operation of said resetting mechanism, said last two means including a plu-
- rality of members operated by either resetting mechanism when said lock is unlocked and cooperating with said arms to prevent removal of said key until the selected resetting operation has been completed.
16. In a locked pick counter, a plurality of counter mechanisms each including a plurality of operatively connected number wheels, independently operable resetting mechanisms for said counter mechanisms including axial rotating elements and cooperating pawl elements within said wheels, a lock having a key, a member carried by said lock and rotatable with said key and having a plurality of arms, and means for separating said elements to blowproof said wheels and for preventing the operation of said resetting mechanism, having elements cooperating with said arms and operated upon partial operation of either resetting mechanism when said lock is unlocked to prevent locking of said counters and withdrawal of said key until the selected resetting operation has been completed.
17. In a locked pick counter mechanism, two counters having adjacent resetting shafts provided with locking portions rotatable therewith, a lock having a key and a swinging locking member controlled by said key and located between said shafts in position to cooperate with the locking portions of both of said shafts for locking the same following resetting.
18. In a pick counter mechanism, two counters having adjacent resetting shafts provided with locking surfaces rotatable therewith, a lock having a key rotatable about an upright axis located between and substantially at right angles to the plane including said shafts, and a locking member controlled by said key and located between said shafts and having operatively connected locking portions extending in opposite directions therefrom and cooperating with said rotatable locking surfaces, and said locking portions having cam faces cooperating with said locking surfaces for rotating said resetting shafts reversely in the same direction upon locking movement of said key following resetting.
19. In a counter, a shaft having a locking surface rotatable therewith and a longitudinal groove, a plurality of operatively connected counter wheels separately rotatable on said shaft, each having a reset pawl engageable with the groove in said shaft for advancing its respective wheel to a common zero position upon 360° rotation of said shaft in a resetting direction, a lock having a key, and means for reversely rotating said shaft to disengage said reset pawls and groove including a swinging locking member carried by said lock and controlled by said key having a locking face out of register with said rotatable locking surface following resetting of said counter wheels and movable into registry therewith during locking by said key.
20. In a locked pick counter mechanism, a plurality of counters each having an axial resetting shaft and operatively connected counter elements rotatable thereon, one of said shafts having a locking portion rotatable therewith, reset operating mechanism for resetting said counters in unison including means operatively connecting said resetting shafts and an operating member for one of said resetting shafts, and locking means governing the resetting of said counters comprising a lock having a key controlling the resetting of said plurality of counters and a swinging locking member controlled by said key and movable in a plane parallel with the plane

including said resetting shafts into and out of engagement with said rotatable locking portion.

21. In a counter having operatively connected counter elements, rotatable resetting mechanism for said counter elements including a resetting shaft and an operating member for the latter, a locking member rotatable with said resetting mechanism, a lock having a key, swinging cam means carried by said lock and operable following resetting and rotatable by said key for engaging said locking member and rotating the same and said resetting shaft reversely during locking of said mechanism by said key, and means for preventing reverse rotation of said resetting shaft to zero position by said operating member following an initial resetting movement having provision for permitting the aforesaid reverse rotation of said shaft during locking.

22. In a locked pick counter mechanism, a counter having operatively connected counting wheels and an axial resetting shaft for returning said wheels to zero position, a locking member rotatable with said shaft having a locking portion, a cooperating swinging locking member adapted to swing into and out of locking position relative to said locking portion, and means governing the resetting of said counting wheels comprising a lock having a key rotatable about an axis disposed transversely of the axis of said resetting shaft and also constituting the operating member for moving said swinging member in opposite directions.

23. In a locked pick counter mechanism, two counters, each having operatively connected counting wheels and having adjacent resetting shafts, locking members rotatable with said shafts each having a locking portion, a swinging locking member located between said shafts in position to cooperate with said locking portions and simultaneously lock said resetting shafts, and locking means also located between said shafts for governing the resetting of said count-

ing wheels comprising a single lock having a key also constituting the operating member for said swinging member.

24. In a pick counter mechanism, two counters having adjacent resetting shafts, a locking member rotatable with one of said shafts, means operatively connecting said shafts for conjoint rotation in the same direction to reset said counters, a common operating member for rotating said shafts, means governing the operation of said operating member comprising a single lock having a key rotatable on an upright axis in a plane perpendicular to said shafts, and a swinging locking member controlled by said key and cooperating with said rotatable locking member in the reset position of said counters to lock said resetting shafts.

25. In a multiple pick counter mechanism, a plurality of counters each having resetting mechanism including a resetting shaft, a plurality of operatively connected counter wheels, and means operatively connecting said shafts for conjoint operation to reset all said wheels simultaneously in the same direction to zero position, a single operating member for said resetting mechanisms, and common locking means for said resetting mechanisms including a locking portion rotatable with one of said shafts having a locking face, a lock having a key, and means controlled by the key cooperating with said locking portion to lock said resetting mechanisms when they have been reset to zero including a swinging locking plate movable into locking relation with said locking portion following resetting movement by said operating member and having a locking face normally out of register with said rotatable locking face following a resetting operation and reversely rotating said resetting shafts as said cooperating faces are brought into registry by the locking movement of said key.

GUSTAVE L. MANKE.
